EBENEZER FISHER AND JOHN WATSON, OF KINCARDINE, ONTARIO,
CANADA.

HORSE-COLLAR FASTENING.

SPECIFICATION forming part of Letters Patent No. 230,261, dated July 20, 1880.
Application filed May 27, 1880. (No model.)

To all whom it may concern:

Be it known that we, EBENEZER FISHER and JOHN WATSON, of Kincardine, Ontario, Canada, have invented a new and useful Improvement in Metallic Horse-Collar Fastenings; and we do hereby declare that the following is a full, clear, and exact description of the same.

Our present invention relates to an improved fastening for metallic horse collars, more particularly for that for which we have received Letters Patent of the United States, No. 224,671.

The fastening is constructed as herein described and claimed.

In accompanying drawings, Figure 1 is a side view of the lower portion of a metallic collar provided with our improved fastening. Fig. 2 is a longitudinal section. Fig. 3 is a plan of the same.

A A' indicate the lower portions of the respective halves of our metallic horse-collar. Said parts are each struck up in the form of half of a hollow cylinder, and have turned edges *a*, which form grooves that receive the edges of the coupling-piece B. The latter is of like form with the parts A A', and is secured to one of them, A, by means of a transverse bolt, C.

The catch or hasp D consists of a flat bar or plate, which is permanently attached to the bolt C at one end, and is provided with a socket, *b*, near its free end to receive and lock with the cross-bolt E, which connects the sides of the collar part A'. The free end of the hasp is bent upward at an angle suitable to adapt it to slide over the bolt E when the two parts A A' of the collar are forced together, and the hasp is held in suitable position to enable it to engage with the bolt E by means of the headed rivet F and the spring G, which encircles the latter—that is to say, the spring G presses the hasp D downward, while the

rivet F limits its movement in that direction. The main function of the spring G is, however, to hold the hasp locked with the bolt E, so that the parts A A' of the collar shall not become accidentally disengaged.

The hasp being attached to part A by means of the bolt C, it is obvious that the adjustment of said bolt in the different holes *c* provided in part A will have the effect of increasing or lessening the distance between the bolts C E, and thereby of enlarging or contracting the size of the collar correspondingly.

The free end *d* of the hasp D is prevented from contact with other objects by which it might be pressed upward and disengaged from bolt E by means of a bolt, H, which connects the flanges of part A', and is arranged below the bent end of the hasp. In some cases, however, we may arrange the catch or hasp to act in the opposite direction from that shown—that is to say, upward.

It will be seen that the bolts C E, in addition to the functions above indicated, serve as rigid stays or braces for the flanges of the collar parts A A', so that the same are greatly strengthened and the durability of the collar increased.

By the above-described construction and arrangement of parts we form a simple, cheap, strong, and adjustable, yet secure and easily-operated, fastening.

What we claim as new is—
The hasp having its free end bent upward and provided with a socket, *b*, and the bolt F and spring G, in combination with the collar parts A A', coupling piece B, and the cross-bolt E, all constructed and arranged as shown and described.

EBENEZER FISHER.
JOHN WATSON.
